VOTING MACHINE FRONT PANEL

Eric S. Stevens, St. Charles, Mo., assignor to Automatic
Voting Machine Corporation, Jamestown, N.Y.

Filed June 4, 1964, Ser. No. 80,294

Term of patent 14 years

(Cl. D26—5)

Fig. 1.

Fig. 2.

FIGURE 1 is a front elevational view of a voting machine front panel, showing my new design;

FIGURE 2 is a fragmentary perspective view thereof on enlarged scale.

The essential features of my design reside in the combination on the voting machine panel disclosed, of the full length selecting means comprising an offset handle, a vertically sliding switch operator and a transparent column cover, as shown in full lines.

In FIG. 1 the curtains are shown as partially deleted so that the ends of the bottom panel will be shown.

While the thickness of the panel is not shown, it is to be understood that it is of conventional thickness.

The selection mechanism, shown in FIGS. 1 and 2, is considered as part of the panel.

I claim:

The ornamental design for a voting machine front panel, substantially as shown and described.
